UNITED STATES PATENT OFFICE.

ADOLPH BOECKELER AND CHARLES S. WISE, OF ST. LOUIS, MISSOURI,
AND ALFRED A. BORDEN, OF LUVERNE, MINNESOTA.

DESIGN FOR AN ACETYLENE-GAS-GENERATOR CASING.

SPECIFICATION forming part of Design No. 32,552, dated April 17, 1900.

Application filed January 8, 1900. Serial No. 797. Term of patent 14 years.

To all whom it may concern:

Be it known that we, ADOLPH BOECKELER and CHARLES S. WISE, residing at the city of St. Louis, State of Missouri, and ALFRED A. BORDEN, residing at Luverne, Rock county, State of Minnesota, citizens of the United States, have invented a certain new and original Design for an Acetylene-Gas-Generator Casing, of which the following is a full, clear, and exact description, reference being had to the accompanying drawing, forming part of this specification.

This invention relates to a new and original design for acetylene-gas-generator casings, in which the characteristic features reside in the circular shape of the casing, which is provided with a box-like projection at its bottom and to one side thereof closed by an ornamental door. Above and in line with said box-like projection is a housing whose outer face is curved concentric to the casing proper. Above this housing is a quarter-sphere, while the top of the casing is convexed and is ornamented by an oblong-shaped crest. Projecting upwardly from the sides of the casing is a bail-like structure. Other details of ornamenting, shape, and configuration will be more clearly brought out in the following description.

In the drawing the figure represents a perspective view of an acetylene-gas-generating casing ornamented and configured according to our new and original design.

In the drawing, A indicates the casing proper, which is cylindrical in shape, and near the bottom of said cylinder, to one side thereof, is provided a box-like projection B.

C indicates an ornamental door or panel, forming the outer wall of said box-like projection.

40

D indicates a housing projecting from the side of the cylinder above and in line with the box-like projection, the outer face of said housing being concentric with the cylinder. The upper end of the cylinder is convexed in shape and ornamented by an oblong-shaped crest E.

45

F indicates a quarter-sphere arranged on the side of the cylinder immediately above the housing D.

50

G indicates cylindrical rods or pipes attached to the cylinder-casing, near the bottom thereof, and extending some distance above the upper end of the cylinder, where said rods are connected by a cross-piece G'.

55

What we claim is—

The design for an acetylene-gas-generator casing, substantially as herein shown and described.

In testimony whereof we hereunto affix our signatures, in the presence of two witnesses, this 28th day of April, 1899.

ADOLPH BOECKELER.

CHARLES S. WISE.

Witnesses as to Boeckeler and Wise:

F. R. CORNWALL,

WM. H. SCOTT.

In testimony whereof I hereunto affix my signature, in the presence of witnesses, this 30th day of September, 1899.

A. A. BORDEN.

Witnesses as to A. A. Borden:

C. J. MARTIN,

F. M. HINKLY.
